APPARATUS FOR AND METHOD OF ANNEALING GLASSWARE

Original Filed April 24, 1923 2 Sheets-Sheet 2

UNITED STATES PATENT OFFICE.

ORIE SHACKELFORD, OF FAIRMONT, WEST VIRGINIA, ASSIGNOR TO HARTFORD-EMPIRE COMPANY, OF HARTFORD, CONNECTICUT, A CORPORATION OF DELAWARE.

APPARATUS FOR AND METHOD OF ANNEALING GLASSWARE.

Application filed April 24, 1923. Serial No. 634,252. Renewed February 16, 1927.

This invention relates to the method of and apparatus for annealing glassware.

The object of the invention is to provide a method and an apparatus for this purpose which will be inexpensive to build, economical to operate, and which will anneal the glassware more rapidly, uniformly, and more nearly perfectly than heretofore.

In order to thoroughly anneal glassware uniformly and at a rapid rate in commercial production by passing it through a leer, it is desirable that all parts of each individual piece of ware, and all of the pieces in each lateral row, shall be at approximately the same temperature at any instant during the progressive annealing process.

More nearly complete uniformity of temperature in the individual pieces and in the different pieces occupying the same position in the length of the leer, is secured when the ware nearly fills the cross-sectional area of the passageway. In order that this approximate filling of the leer may be maintained with successive lots of ware varying in size, one of the features of the invention resides in the provision of a leer having means to permit adjustment of the cross-sectional area of the ware passageway in accordance with the size of the ware being made.

The filling out of the lateral width of the leer passage can be taken care of quite closely by the number of pieces stacked in each lateral row. Therefore, the invention is more particularly directed to provisions for changing the vertical height of the leer passage, preferably by adjusting the upper wall of the passage toward and from the bottom so as to maintain a minimum clearance between the top of the ware and the top wall of the leer.

In order to prevent the outside pieces of ware from being cooled more rapidly than the inner pieces when the ware is fed through the leer in a plurality of rows, the walls of the leer are made of material having a low heat absorbing and conducting capacity, and insulation is provided to reduce the heat losses of the ware.

Another object of the invention is to provide new and improved means for controlling the temperature of the leer, by inclining it longitudinally from a horizontal plane and providing means for adjusting the angle of inclination whereby the tendency of the

heated atmosphere to rise to the higher end of the leer may be utilized and regulated.

Another object of the invention is to provide a new method of operating a leer whereby the ware may be annealed by its own heat which it carries into the leer, without the necessity of reheating the ware between the time that it is formed and the time when annealing is completed, or in other words, without supplying additional heat after the ware leaves the molds. I have found that glassware may be annealed by the heat remaining in it, if transferred quickly into the leer from the mold, or if its initial heat is otherwise prevented from escaping too rapidly from the immediate environment of the ware.

The various features employed to attain these objects and such other objects as may be apparent from the following description, will best be understood by reference to the following specification and the accompanying drawings of one embodiment of the invention, in which:—

Figure 1 is a perspective view of the leer; 80

Fig. 2 is a side elevation in section on a plane extending longitudinally of the leer;

Fig. 3 is a partial end elevation in section on an enlarged scale taken on line 3—3 of Fig. 2; 85

Fig. 4 is an enlarged detail in side elevation, showing particularly the means for holding the adjustable top of the leer in adjusted position;

Fig. 5 is a detail in perspective of one of the sliding covers which close the opening through which the ware is inserted in the leer; and 90

Fig. 6 is an end elevation in section of a modified form of tunnel wall construction. 95

The preferred embodiment of the invention comprises a floor 10 (Figs. 2 and 3) connected by angle irons 11 with side walls 12, which form the bottom and sides of the tunnel through which the ware is passed. In order that the cross sectional area of the tunnel may be adjusted, the top of the leer is a separate structure, comprising a top plate 13 and depending double side walls 14, 15 (Fig. 3). These walls are separated to receive the wall 12 and form a telescoping connection therewith.

Means are provided for holding the top wall spaced from the bottom wall at different positions, each slightly greater than the 110

height of the ware then being made, (Figs. 2 and 3). One means which may be used for this purpose comprises a rack 16 (Fig. 4), fixed to the side wall 12 at each of the four corners of the leer. Pivots mounted between the side wall 14 and a bracket 18 attached thereto is a pawl 17 which engages one of the teeth of the rack and holds the top wall in adjusted position. This arrangement 10 may be reversed by attaching the pawl to the side wall 12 and the rack to the adjustable top.

All of the tunnel walls are preferably provided with heat insulating means, which may 15 be of suitable material and thickness to reduce the heat loss to the desired extent. Such an insulation is indicated at 19 (Figs. 2 and 3). Fig. 6 shows another insulated construction which may be employed in leers 20 having an adjustable top wall or in leers of fixed cross sectional area shown in this figure. In this construction the walls comprise a sheet metal lining 22 and a larger outer casing 23, the space between the lining and 25 the casing being filled with any suitable heat insulating material 24, such, for example, as mineral wool or kieselguhr.

Any suitable mechanism may be provided for advancing the ware through the tunnel, 30 but as illustrated, the ware is carried through the leer in pans 26, which are supported by the angle irons 11 (Fig. 3). If desired, the bottom of the pans may be perforated in any manner and rolls may be provided to support the pans. The angle irons 11 project at both ends of the leer (Fig. 1) so that the pans may be placed on the irons outside of the leer and pushed in, and after passing through the tunnel they emerge outside the 35 tunnel walls, still supported by the other ends of the angle irons. The left, or receiving end of the leer, is provided with a portion of reduced height, as indicated at 27, which with the in-coming pan 26, substantially closes that end of the tunnel. A swinging door 28 is provided to maintain the same degree of closure, when the top is adjusted to a higher position than that shown in Fig. 2.

50 The ware is placed in one of the pans 26 through an opening 29, (Fig. 1) on the top and front wall of the leer. As each article is placed in the pan, a sliding cover 30 is moved along to cover the deposited ware, and to 55 open the adjacent space for the next piece. After a complete row of ware has been inserted, the projecting pan 26 is pushed in enough to bring an empty part of the pan below the opening 29 to receive another row.

60 The delivery end of the leer is provided with a swinging door or closure 31 to minimize or regulate the entrance of cold air.

65 The flow of heated air and the heat variations longitudinally of the leer may be controlled within certain limits by varying the

longitudinal inclination of the top of the passageway or the whole passageway through which the ware travels. In order to provide this angular adjustment, the leer is pivotally mounted at one end, preferably 70 the ware receiving end, and means are provided for supporting the other end at any desired height. The receiving end of the leer may be supported at a fixed elevation by a pair of legs 34 (Fig. 1), pivotally connected with the leer by studs 35, while the delivery end of the leer is supported by a pair of legs 36 provided with a series of holes 37 adapted to receive pins 38. The inclination of the leer may be adjusted by removing the pins 38 and raising or lowering the end of the leer to the desired extent, after which the pins are inserted in the proper holes.

The temperature of the leer may be further adjusted by permitting a controlled escape of air at one or more points in its length. For this purpose one or more stacks 39 are provided, each extending transversely of the leer and each having a damper 40 by 80 which the extent of the stack opening may be regulated.

The leer of the present invention may be used without supplying additional heat to the ware therein, provided the ware is placed in the leer in sufficient quantity, and with sufficient continuity, and while it retains sufficient heat from its original molten condition, to provide the necessary annealing temperature. For this purpose, the insulation indicated at 19 should be sufficient to prevent too great a loss of heat until after the critical annealing temperature has been passed. When the apparatus is thus used as a "self-heat" leer, in which the annealing heat is supplied by the glassware itself, it may sometimes be desirable to supply additional heat just prior to or during the insertion of the first lot of ware, in order to bring the leer to working temperature, and the same heating means may be employed for supplementing the heat of the glassware whenever the latter is not fed in rapidly enough or continuously enough, or with sufficient heat, as for example when the making 115 of the glassware is interrupted for any reason.

In other words, the operation as a self-heat leer is dependent upon a supply of heat in the glassware, delivered to the leer sufficient in degree and in continuity to compensate for the heat losses occurring in the leer, and to maintain the interior near the receiving end at a temperature not lower than the critical annealing temperature of the ware. For example, if the leer is being fed by ware produced by two presses, and one of the presses is stopped, then the heat delivered to the leer will be correspondingly reduced, and this may be insufficient to prop- 120 125 130

erly anneal the ware. In such cases, one or more of the burners may be turned on sufficiently to compensate for the reduction.

The heating means shown in the drawing 5 comprises two chambers 43 and 44. The chamber 43 may be carried by or formed integral with the adjustable top wall, and both chambers may be separated from the interior of the lehr by plates 45, forming 10 muffles. Heat is supplied to the chambers by gas pipes 46 having a series of burners 47 projecting into the chambers 43 and 44. Any of the well known forms of burners and controlling means therefor may be provided.

15 The lehr may be of any desired length, and instead of being straight, as herein shown, it may be arranged in a spiral, like a spiral stairway. The downward inclination toward the delivery end is of advantage 20 in making it easier to advance the ware through the tunnel, whether the feed is by hand or automatic.

25 The preferred construction of the apparatus has been illustrated and described by way of example only, and it is to be understood that various modifications and changes may be made without departing from the spirit of the invention as defined by the appended claims.

30 I claim:

1. A lehr comprising a passageway having a fixed floor, means supported by said floor for transporting a continuous series of articles through said passageway, and means 35 for varying the cross sectional area of said passageway.

2. A lehr comprising a passageway having a fixed floor, means mounted for movement adjacent to said floor for transporting 40 a series of articles through said passageway, and means for varying the cross sectional area of said passageway.

3. A lehr comprising a passageway having a fixed floor, means for heating said 45 floor, means supported by said floor for transporting a continuous series of articles through said passageway, and means for varying the cross sectional area of said passageway.

50 4. A lehr comprising a muffle chamber having a fixed floor, means for heating said floor, means for transporting a continuous series of articles through said chamber, and means for varying the cross sectional area 55 of said chamber.

5. A lehr comprising an elongated muffle chamber or tunnel having side walls and a top wall and a fixed floor, one of said walls being adjustable to vary the cross sectional 60 area of said passageway, a heating chamber beneath said floor, means for supplying a heating medium to said heating chamber to heat said floor, and means for transporting a continuous procession of articles through said tunnel.

6. A lehr having an adjustable top wall, a heating device carried by the top wall, and means to hold the top wall and heating device in adjusted position.

7. A lehr comprising a passageway having a fixed wall and a movable wall, a heating chamber for exteriorly heating said fixed wall, means supported by said fixed wall for transporting a continuous procession of articles through said passageway, 75 and means for adjusting the movable wall toward and away from said fixed wall to vary the cross sectional area of said passageway.

8. A lehr having a passageway provided with a vertically adjustable top wall, and a closure for the passageway adjustable to compensate for the adjustments of the top wall.

9. A lehr comprising a tunnel inclined in 85 the direction of its length, and means to permit adjustment of the angle of inclination.

10. A lehr having a movable top wall, 90 and means to permit adjustment of the angle of inclination of the top wall to regulate the flow of air toward the higher end.

11. A lehr having top, side and bottom members forming a passageway for the ware, means to permit adjustment of one of said members to vary the cross sectional area of the passageway, and heat insulating material movable with the adjustable member.

12. A lehr having an angularly adjustable top wall and a stack connected therewith.

13. Apparatus for annealing glassware, comprising a heat retaining chamber having an opening for the introduction of ware, and a series of sliding covers for the opening in number less than the number sufficient to close the opening.

14. Apparatus for annealing glassware, comprising a heat retaining chamber having an opening for the introduction of ware, 110 and a sliding cover therefor of less width than the opening adapted to be moved laterally to expose openings alternately on opposite sides thereof.

15. Apparatus for annealing glassware, comprising a heat retaining chamber having an opening for the introduction of ware, and a cover therefor mounted for movement transversely of the chamber, said cover having surfaces at an angle to each other.

16. A lehr having relatively movable top and bottom walls and overlapping side walls connected therewith.

17. A lehr having relatively movable top and bottom members, and telescoping side 125 walls connected with said members.

18. A lehr having relatively movable top and bottom members, a heating device carried by each of said members, pans movable through the lehr, means to permit introduc-

ing ware into the pans between the ends of the lehr, and means to permit adjustment of the angular position of the lehr.

19. The method of regulating the heat of a glass annealing lehr, which includes the step of changing the inclination of a conducting passage of the lehr to control the flow of air therethrough.

20. The method of regulating the heat of a glass annealing lehr, which includes the step of lowering the delivery end of the lehr to increase the influx of air through the lehr.

21. The method of regulating the heat of a glass annealing lehr, which includes the step of lowering one end of the lehr to cause the air to rise more rapidly toward the other end.

22. A lehr having a tunnel, means for moving the ware through the tunnel, and means to permit adjustment of the cross sectional area of the tunnel.

23. A lehr comprising side and bottom walls and a top forming a tunnel, means for moving the ware through the tunnel, and

means to permit adjustment of one of the tunnel-forming members to vary the cross sectional area of the tunnel.

24. A lehr comprising side and bottom walls and a top forming a tunnel, mean for moving the ware through the tunnel, and mean to permit vertical adjustment of the top and the bottom of said tunnel relative to each other to vary the height of the tunnel.

25. Apparatus for annealing glassware comprising a tunnel, means for transporting articles of glassware therethrough, and means disposed intermediate the ends of said tunnel for withdrawing gases therefrom throughout substantially the entire width thereof.

26. Apparatus for annealing glassware comprising a tunnel, means for transporting articles of glassware therethrough, and a stack disposed intermediate the ends of said tunnel and extending substantially across the entire width thereof.

Signed at Fairmont, W. Va., this 18th day of April, 1923.

ORIE SHACKELFORD.
